[57] ABSTRACT

In the present invention, a combination of four valves arranged to form a bridge is coupled to a temperature-pressure transducer that interconnects the input and output channels of the bridge according to whether the ambient environment of the transducer is relatively warm or cool. More specifically, the transducer is coupled to both a low pressure source and a high pressure source and will apply one combination of such pressures to the bridge if the transducer environment is relatively cool and another combination of such pressures if the transducer environment is relatively warm. In response to these signals, one pair of another of the valves in the bridge are closed, with the result that the connections between the bridge's input and output channels are thereby reversed.

**TEMPERATURE-SENSITIVE REVERSING VALVE
APPARATUS**

The present invention relates to valves in general and more particularly relates to a valve apparatus that is sensitive to changes in ambient temperature conditions to reverse gas-flow and gas-pressure connections in a system.

In systems in which gases flow and gas pressures are applied, it is oftentimes desirable, if not necessary, to reverse the connections of some of the ducts or channels in the system with changes in operating conditions. It is desirable to do so, for example, in certain types of air-conditioning systems when the conditioned air flowing therein changes from hot to cold or vice versa. More specifically, in order to maximize the effectiveness and minimize the costs of such air-conditioning systems, it is desirable as a part of their operation to first detect or determine whether hot or cold air is flowing at a point in the system and then to connect certain ducts or channels in the system in one way if the system is operating in a cooling mode and to reverse those connections if the system is operating in a heating mode.

The present invention meets the above-said needs or requirements of such systems by providing a unique combination of temperature-pressure transducer and reversal valve, the transducer applying one or the other of a pair of gas-pressure signals to the reversal valve, depending, respectively, on whether the ambient environment of the transducer is relatively hot or cold and the valve, in response to those signals, connecting a pair of input channels in one way or another to a pair of output channels.

More particularly, the transducer's two outputs are coupled directly to a relatively low-pressure source and through a pair of thermostatically-controlled valves are also coupled to a relatively high-pressure source. Only one or the other of the valves is open at any one time, with the result that when the transducer is in a relatively cool environment, one output produces the high pressure and the other output produces the low pressure. On the other hand, when the transducer environment is relatively warm, the pressures produced at its two outputs are reversed. The transducer valves governing these pressures are opened and closed in response to the motion of a coiled bi-metallic strip and, consequently, are opened and closed in response to changes in ambient temperature conditions. As for the reversal valve, it comprises four valves connected in tandem to form a closed loop, a pair of input channels and a pair of output channels being connected between the valves to form a bridge-circuit arrangement of them. The valves are preferably disc-shaped chambers with orifices in their rooves by means of which they are interconnected. In each valve is also located a diaphragm resting on the floor of the valve chamber and which may be raised and pressed against the roof of the chamber to cover the orifices there, thereby closing that particular valve. By thusly closing one pair or the other of the valves diagonally opposing each other in the bridge, the connections between the input and output channels can be reversed. The diaphragms can be raised or lowered by respectively applying relatively high or low pressures to their undersides through orifices located in the floors of the valve chambers. Needless to say, by applying the transducer output pressures to these valves, the desired connections

between the input and the output channels can be obtained. Ultimately, therefore, the input and output channel connections are determined by whether the air-conditioning system is in a cooling or heating mode.

5 It is, therefore, an object of the present invention to provide the means to automatically reverse certain connections in an air-conditioning system when the system shifts from a cooling mode to a heating mode, or vice versa.

10 It is another object of the present invention to provide apparatus to detect whether the gases flowing in a system are relatively hot or cold and to switch channel connections in the system in accordance therewith.

15 It is a further object of the present invention to provide an apparatus that utilizes the temperatures and pressures of gases flowing in a system to change connections therein.

20 It is an additional object of the present invention to provide the means to maintain the effectiveness of certain types of air-conditioning systems when they shift from the cooling mode to the heating mode, or vice versa.

25 The novel features which are believed to be characteristic of the invention, both as to its organization and method of operation, together with further objects and advantages thereof, will be better understood from the following description considered in connection with the accompanying drawing in which an embodiment of 30 the invention is illustrated by way of example. It is to be expressly understood, however, that the drawing is for the purpose of illustration and description only and is not intended as a definition of the limits of the invention.

35 FIGS. 1a and 1b are block diagrams, partly in schematic form, illustrating the basic purposes and principles of a temperature-sensitive reversing valve apparatus according to the present invention;

40 FIG. 2 is a diagram illustrating the basic structure of a preferred embodiment of a temperature-sensitive reversing valve apparatus according to the present invention;

45 FIG. 3 is a front view of the temperature-pressure transducer included in the FIG. 2 apparatus;

FIG. 4 is a side view of the temperature-pressure transducer included in the FIG. 2 apparatus; and

50 FIG. 5 is an exploded view showing in detail one of the four valves utilized in the FIG. 2 apparatus.

To provide a preliminary understanding of the invention, reference is now made to FIGS. 1a and 1b of the drawing wherein the basic concept of the invention is depicted. The reversing valve portion of the overall apparatus is designated therein as 10, the transducer portion of the overall apparatus is designated 11, inlet channels leading into reversing valve 10 and through which gases are fed or gas pressures applied to it are designated I_1 and I_2 , and channels leading out of reversing valve 10 are designated O_1 and O_2 . As shown in FIG. 1(a), in response to a gas-pressure signal S_1 produced by transducer 11 and applied to reversing valve 10, the reversing valve respectively interconnects inlet channels I_1 and I_2 to outlet channels O_1 and O_2 . In this instance, therefore, any gas flowing in inlet channel I_1 enters outlet channel O_1 and the same is true with respect to channels I_2 and O_2 . On the other hand, FIG.

60 1(b) shows what happens when a gas-pressure signal S_2 is applied to transducer 11. In this instance, the reversing valve interconnects inlet channels I_1 and I_2 to outlet channels O_2 and O_1 . In this instance, therefore, any gas flowing in inlet channel I_1 enters outlet channel O_2 and the same is true with respect to channels I_2 and O_1 .

is applied by the transducer to the reversing valve. In this latter instance, the connections between the inlet and outlet channels are reversed, that is to say, inlet channel I_1 is now connected to outlet channel 0_2 and, similarly, inlet channel I_2 is now connected to outlet channel 0_1 . In both figures, within the block designated as reversing valve 10, the broken line indicates the above-described connections between the channels.

Considering now the invention in greater detail, reference is made to FIG. 2 wherein, in a preferred embodiment of a temperature-sensitive reversing valve apparatus according to the present invention, reversing valve 10 is shown to basically include a plurality of four valves, respectively designated 12-15 that are connected to one another in series or, stated differently, in tandem by a corresponding plurality of four flow channels respectively designated 16-19. Inlet channels I_1 and I_2 respectively connect to flow channels 16 and 18, whereas outlet channels 0_1 and 0_2 respectively connect to flow channels 19 and 17, with the result, as will be recognized by those skilled in the art that valves 12-15, connecting flow channels 16-19, inlet channels I_1 and I_2 , and outlet channels 0_1 and 0_2 , combine to form a bridge-circuit arrangement. Finally, the embodiment includes still another pair of channels 21 and 22, hereinafter sometimes referred to as control channels, and still another pair of inlet channels 23 and 24, control channels 21 and 22 respectively interconnecting the two pairs of diagonally opposing valves shown in FIG. 2. Thus, control channel 21 interconnects valves 13 and 15 and control channel 22 interconnects valves 12 and 14. As for inlet channels 23 and 24, these are connected between control channels 21 and 22, respectively, and temperature-pressure transducer 11 which, it will be remembered, produces gas-pressure signals S_1 and S_2 mentioned earlier in connection with FIGS. 1a and 1b.

Valves 12-15 are preferably identical to one another and, as can be seen from FIG. 5 wherein one of the valves is shown in greater detail, each resembles a disc-shaped chamber. For sake of convenience and clarity, the valve shown in FIG. 5 and to be described hereinbelow shall be considered to be valve 13 in FIG. 2, but it will be understood that the description will be equally applicable to all the valves. Accordingly, referring to FIG. 5, valve 13 therein basically includes a roof member 13a, a floor member 13b, and a diaphragm 13c. Members 13a and 13b are disc-shaped and recessed with the result that when they are put together, one upon the other and sealed, they form the aforesaid disc-shaped valve chamber.

Roof member 13a has two orifices through it designated 13d and 13e and although one orifice is shown located at the center of the member and the other is shown located at its outer periphery, it must be emphasized that the actual location of these orifices is relatively unimportant, that is to say, that their location is merely a matter of design. Floor member 13b has one orifice through it designated 13f and here again its actual location is only a matter of design. Floor member 13b also has a circular crevice or recess 13g located in its rim and the function of this recess is to properly locate and hold or, stated differently, to properly seat diaphragm 13c when it is on the floor of the valve chamber. In this regard, diaphragm 13c has a circular

lip 13h integral with its underside which, as shown by the broken lines 13i, fits into recess 13g and thereby helps to seat the diaphragm. The diaphragm includes another circular lip 13j that is centered on its top surface, 5 the lip enclosing orifice 13d, as shown by broken line 13k, when the diaphragm is pressed against the roof of the valve. Finally, although not essential, diaphragm 13c preferably also includes another circular lip 13l centered on its underside, lip 13l making contact with the floor of the valve, as shown by broken line 13m, when the diaphragm is seated on member 13b. The function of lip 13l is to facilitate the separation of the diaphragm from the surface of member 13b when the operation calls for such a separation.

Considering now the operation of the FIG. 5 valve, which is the operation of all the valves, it will initially be assumed that no gas pressure is being applied to the underside of diaphragm 13c, which, when applied, is applied through orifice 13f. Accordingly, diaphragm 13c is on the floor of the valve, that is to say, it is seated on member 13b, with the result that orifices 13d and 13e are uncovered or exposed which, in turn, means that any gas flowing through one of these orifices will thereafter flow through the other. Under such circumstances, the valve is said to be "open." If, now, a suitable gas pressure is applied through orifice 13f to the underside of diaphragm 13c, the diaphragm will be raised and pressed against the roof of the valve chamber, that 10 is to say, against the undersurface of member 13a, thereby covering over or otherwise closing at least one of the two orifices there. More specifically, with diaphragm 13c raised against roof member 13a, orifice 13d is covered over in an airtight manner and, in the 15 subject embodiment, so is orifice 13e. When one or both of these orifices are closed in the manner described, there can be no flow between them and the valve is then said to be "closed." When the gas pressure that raised diaphragm 13c is removed, the diaphragm 20 falls to member 13b and again becomes seated there, with the result that the valve is now open once again.

At this point it would be well to refer once again to FIG. 2 and to mention that flow channel 17 therein intercouples valves 12 and 13 via orifices 12d and 13d, 25 that flow channel 18 intercouples valves 13 and 14 via orifices 13e and 14e, that flow channel 19 intercouples valves 14 and 15 via orifices 14d and 15d and, finally, that flow channel 16 intercouples valves 12 and 15 via orifices 12e and 15e. All of the orifices mentioned are 30 in the rooves of the several valves, just as is shown in FIG. 5 and described in connection therewith. It should also be mentioned that orifices 12f-15f are respectively in the floors of valves 12-15, and that control channel 21 intercouples valves 13 and 15 via orifices 13f and 15f while control channel 22 intercouples valves 12 and 14 via orifices 12f and 14f. Of course, although not shown in FIG. 2, each of the valves therein includes a diaphragm of the kind shown in FIG. 5 that is interposed between its roof and floor members. It should 35 finally be mentioned with respect to the signals generated by transducer 11 that signal S_1 comprises a low pressure on inlet channel 23 and a high pressure on inlet channel 24 and signal S_2 comprises a high pressure on inlet 23 and a low pressure on inlet channel 24. The manner in which these signals are generated will be explained in connection with the description of transducer 11 to which reference is now made.

Directing attention to FIGS. 2, 2 and 4, the transducer is shown to preferably include a pair of members 25a and 25b through which a pair of channels 26a and 26b respectively extend. Tubing or similar type devices are coupled at one end to the input ports of channels 26a and 26b, as shown in the figures, and at the other or forward end they are coupled to a relatively low pressure source (not shown), the tubes respectively being designated 27a and 27b. To rigidly mount and hold members 25a and 25b in place, the transducer also includes a pair of crossbars 28 and 29 to which members 25a and 25b are cemented or otherwise fastened, with the result that all four members form a rigid unit.

Rotatably mounted between crossbars 28 and 29 is a shaft 31, the ends of the shaft extending into these members as shown in the figures. A coiled bi-metallic strip 32 is mounted on shaft 31, the center of the coil being rigidly fastened to the shaft so that in the event of any rotative movement of the coil, the coil and the shaft will rotate together. The other end of the coil, designated 32a, extends from the body of the coil to member 25b where it is fixed in position just above the member by means of a nail or screw 33 which passes through end 32a and into member 25b. A spring 34 is mounted on the nail or screw between end 32a and member 25b, the spring forcing the coil end up against the head of the nail or screw and thereby preventing it from easily moving up and down.

Respectively connecting with channels 26a and 26b are a pair of identical valves, generally designated 35 and 36, that comprise a pair of passageways or channels 35a and 36a and a plate or bar 37 that is rigidly mounted in see-saw fashion on shaft 31. For reasons that will be seen later, plate or bar 37 is made of a magnetizable material. Channels 35a and 36a respectively extend downward from the top surfaces of members 25a and 25b until they connect or couple with channels 26a and 26b, extending or lying over the entrances or openings to channels 35a and 36a. In order to ensure an affirmative and effective opening and closing action for valves 35 and 36, there is preferably also provided, first, a pair of circular lips 35b and 36b that are respectively mounted on the surfaces of members 25a and 25b around the openings to channels 35a and 36a and, second, a pair of felt pads 38a and 38b respectively mounted on the underside of plate or bar ends 37a and 37b. As shown in the figures, pads 38a and 38b respectively overlie lips 35b and 36b and effectively cover the openings to channels 35a and 36a when they are brought into contact with these lips.

At this point, it would be well to mention that several things can be done and, preferably, are done to obtain a speedy response from valves 35 and 36 and, therefore, from the transducer itself. First, the load on coil 32 is reduced to a minimum and this can be achieved by keeping the weight of plate 37 and pads 38 to a practical minimum. This, in turn, can be achieved by choosing materials of relatively light weight for them and by keeping their thicknesses to a practical minimum. Second, the spacing between the pads and the lips are made as small as possible. Third, the distance through which the ends of plate 37 travel are also kept as small as possible, that is to say, to within necessary limits only, and this is done by providing another pair of lips 39a and 39b on the top surfaces of members 25a and 25b, respectively, preferably at the outer edges thereof,

against which the ends of plate 37 respectively abut as one or the other of the valves is closed.

Finally, a preferred embodiment of the transducer also includes a pair of magnets 41a and 41b mounted on a cross bar 42. Magnets 41a and 41b are mounted beneath plate or bar 37 intermediate shaft 31 and members 25a and 25b, the primary purposes or functions of the magnets being, first, to bias plate or bar 37 to ensure that one or the other of the valves will at all times be closed and, second, to apply slight restraining forces on the plate or bar that will cause the valves to open and close at slightly different temperatures, thereby helping to avoid spurious openings and closings due to slight fluctuations in temperature that may occur about the set points of the valves. By "set point" is meant the temperature at which each valve is designed to close. By way of example, if valve 36 is designed to close and valve 35 to open at 76 degrees Fahrenheit and valve 35 is designed to close and valve 36 to open at 74 degrees Fahrenheit, then 76 degrees and 74 degrees are respectively the set points for these valves and the temperatures therebetween form what may be termed a "dead band" in which the states or conditions of the valves are not affected. Thus, if valve 36 is closed, which means valve 35 is open, then a momentary fluctuation of the ambient temperature to 75 degrees Fahrenheit will not affect the situation and valve 36 will remain closed. The same is true if valve 35 is closed and valve 36 open. It will be recognized by those skilled in the art that by suitable design, the set points can be brought further together or apart, as desired.

In considering the operation of this transducer, it will be assumed that it is located in a relatively high pressure environment and, as previously mentioned, that tubes 27a and 27b extend therefrom and couple to a relatively low pressure environment. Thus, through valves 35 and 36, channels 26a and 26b are respectively exposed to a relatively high gas pressure and through tubes 27a and 27b to a relatively low gas pressure. It will also be initially assumed, that the ambient temperature is high enough so that valve 36 is closed, with the result that the output signal produced by the transducer is the aforesaid signal S_1 , namely, a high pressure in inlet channel 24 and a low pressure in inlet channel 23. This is so because with valve 36 closed, the high pressure of the ambient environment cannot get through to channel 26b and from there to inlet channel 23. Of course, the reverse is true on the other side of the transducer where valve 35 is open.

If, now, the temperature of the environment in which the transducer is located drops to the set point of valve 35 or below, bi-metallic coil will contract sufficiently to rotate shaft 31 and, therefore, plate 37, in a counter-clockwise direction to thereby close valve 35 and, simultaneously therewith, open valve 36. When this occurs, the output signal produced by the transducer is then signal S_2 , namely, a low pressure in inlet channel 24 and a high pressure in inlet channel 23, just the reverse of the earlier signal.

The transducer will return to its former state if the ambient temperature should rise to at least the set point of valve 36. Under such circumstances, bi-metallic coil 32 will expand and thereby enter into a clockwise rotational movement which, when the set point is reached,

causes shaft 31 and, therefore, plate 37 to likewise rotate in a clockwise direction. With the clockwise rotation of plate 37, valve 36 is thereby closed and, simultaneously therewith, valve 35 is opened. At this point, the output signal is again a high pressure in inlet channel 23 and a low pressure in inlet channel 24.

Considering now the operation of reversing valve 10 in FIGS. 2 and 5, when signal S_1 is applied to inlet channels 23 and 24, the low pressure in inlet channel 23 is applied through channel 21 and orifices 13f and 15f to the underside of the diaphragms in valves 13 and 15, the effect thereof being that the diaphragms are kept seated on the floors of those valves. On the other hand, the high pressure in inlet channel 24 is applied through channel 22 and orifices 12f and 14f to the underside of the diaphragms in valves 12 and 14, the effect thereof being that the diaphragms are thereby raised to and pressed against the roofs of these valves. In consequence of the above and in accordance with the descriptive material presented hereinabove, valves 12 and 14 are closed and valves 13 and 15 are open. Accordingly, any gas entering inlet channel I_1 flows into channel 16 and from there into and through valve 15 to channel 19 where it exits via outlet channel O_1 . By tracing the path between inlet channel I_2 and outlet channel O_2 in the same way, it would likewise be found that gas flowing into inlet channel I_2 will ultimately flow out of outlet channel O_2 . Thus, when a signal such as signal S_1 is applied to reversing valve 10, inlet channel I_1 and I_2 are respectfully connected to outlet channels O_1 and O_2 just as it is illustrated in FIG. 1(a).

If, now, instead of signal S_1 , signal S_2 is applied to inlet channels 23 and 24, the high pressure in inlet channel 23 is, as before, applied through channel 21 and orifices 13f and 15f to the underside of the diaphragms in valves 13 and 15. This time, however, the diaphragms are raised and pressed against the roofs of these valves to effectively close them. On the other hand, due to the fact that the pressure on inlet channel 24 is now relatively low, valves 12 and 14 are open. Thus, when signal S_2 is applied, a gas entering inlet channel I_1 must now pass through valve 12 since valve 15 is closed and, therefore, make its exit via outlet channel O_2 . In the same way, gas flowing in inlet channel I_2 can be traced through valve 14 to outlet channel O_1 . It can therefore be seen that signal S_2 reverses the connections between inlet channels I_1 and I_2 and outlet channels O_1 and O_2 , as illustrated in FIG. 1b.

Although a particular arrangement of the invention has been illustrated above and described herein by way of example, it is not intended that the invention be limited thereto. Accordingly, the invention should be considered to include any and all modifications, alterations or equivalent arrangements falling within the scope of the annexed claims.

Having thus described the invention, what is claimed is:

1. Apparatus for reversing the connections between a pair of inlet channels and a pair of outlet channels through which gases flow and gas pressures applied, the inlet and outlet channels being connected in one way in response to a relatively warm ambient environment and in another way in response to a relatively cool ambient environment, said apparatus comprising: reversing

valve means including first, second, third and fourth valves, each being adapted to open and close, respectively, in response to first and second gas pressures applied thereto, first, second, third and fourth flow channels connected between said valves to form a closed loop arrangement in which valves and flow channels are alternately connected in the loop, the first and third of said flow channels respectively being connected to the pair of inlet channels and the second and fourth of said flow channels respectively being connected to the pair of outlet channels; and temperature-pressure transducer means coupled to said reversing valve means and to relatively high and low gas-pressure sources, said transducer means including additional means operable in response to ambient temperature conditions to apply a first gas-pressure signal to said valves to connect the inlet and outlet channels the one way when the ambient environment is relatively warm and a second gas-pressure signal to said valves to connect the inlet and outlet channels the other way when the ambient environment is relatively cool.

2. The apparatus defined in claim 1 wherein each valve has first and second orifices to which flow channels are coupled, a third orifice to which said temperature-pressure transducer means is coupled, and a diaphragm adapted to close at least one of said first and second orifices interposed between said first and second orifices on the one hand and said third orifice on the other hand.

3. The apparatus defined in claim 1 wherein said reversing valve means further includes first and second control channels respectively having first and second inputs thereto to which said first and second signals are applied, said first control channel being connected between the first and third of said valves and said second control channel being connected between the second and fourth of said valves.

4. The apparatus defined in claim 1 wherein said first and second gas pressures are respectively low and high pressures, and wherein said first signal is a first combination of said first and second gas pressures and said second signal is a second combination thereof.

5. The apparatus defined in claim 1 wherein said additional means includes first and second channels coupled to said low pressure source; first and second valves coupled between said first and second channels, respectively, and said high pressure source; and temperature-responsive means for simultaneously closing one and opening the other of said transducer valves.

6. The apparatus defined in claim 2 wherein said first flow channel is coupled between the second orifices in said first and second valves, said second flow channel is coupled between the first orifices in said second and third valves, said third flow channel is coupled between the second orifices in said third and fourth valves, and said fourth flow channel is coupled between the first orifices in said first and fourth valves.

7. The apparatus defined in claim 2 wherein said reversing valve means further includes first and second control channels respectively having first and second inputs thereto to which said first and second signals are applied, said first control channel being coupled between the third orifices in said first and third valves, and said second control channel being coupled between the third orifices in said second and fourth valves.

8. The apparatus defined in claim 2 wherein each of said four valves and the diaphragm therein is adapted to seat said diaphragm over the third orifice in said valve in response to said first gas pressure and to press said diaphragm against said first and second orifices in said valve in response to said second gas pressure.

9. The apparatus defined in claim 2 wherein each of said four valves includes a floor member in which said third orifice is located and a roof member in which said first and second orifices are located, said floor member and diaphragm being adapted to normally seat said diaphragm on said floor member and operable in response to said second pressure to raise and press said diaphragm against said roof member.

10. The apparatus defined in claim 2 wherein each of said diaphragms includes a circular lip on its bottom side that is positioned to encircle the third orifice, and a circular lip on its topside that is positioned to encircle the first orifice.

11. The apparatus defined in claim 5 wherein said temperature-responsive means includes a rotatably mounted shaft; a member mounted on said shaft and rotatable therewith, said member being adapted to simultaneously close one and open the other of said transducer valves in response to rotation of said shaft; and a coiled bi-metallic strip coupled to rotate said shaft in clockwise and counterclockwise directions in response to changes in temperature.

12. The apparatus defined in claim 5 wherein said temperature-responsive means includes a coiled bi-metallic element mounted to move in clockwise and counterclockwise directions in response to changes in temperatures, and apparatus couples between said bi-metallic element and said transducer valves, said apparatus being operable when said element moves in a clockwise direction to open and close said first and second transducer valves, respectively, and operable when said element moves in a counterclockwise direction to close and open said first and second transducer valves, respectively.

13. The apparatus defined in claim 6 wherein said reversing valve means further includes first and second control channels respectively having first and second inputs thereto to which said first and second signals are applied, said first control channel being coupled between the third orifices in said first and third valves, and said second control channel being coupled between the third orifices in said second and fourth valves.

14. The apparatus defined in claim 11 wherein said member is made of a magnetizable material and wherein said additional means further includes a pair of magnets mounted beneath said member intermediate said shaft and valves.

15. The apparatus defined in claim 11 wherein said first and second transducer valves respectively include first and second passageways that respectively connect with said first and second channels, and wherein said transducer means includes elements that cooperate with said member for closing the entrances to said passageways.

16. The apparatus defined in claim 12 wherein said apparatus includes a shaft rotatably mounted between said transducer valves and coupled to said bi-metallic

5 element to rotate with the movement therewith; and a plate mounted in see-saw fashion on said shaft and extending over said transducer valves, said plate rotating with said shaft to close one and open the other of said transducer valves.

17. The apparatus defined in claim 13 wherein each of said four valves and the diaphragm therein is adapted to seat said diaphragm over the third orifice in said valve in response to said first gas pressure and to press said diaphragm against said first and second orifices in said valve in response to said second pressure.

18. The apparatus defined in claim 15 wherein said member is a plate mounted in see-saw fashion on said shaft and extending over said transducer valves, and wherein said elements include felt-like pads respectively mounted on the ends of said plate on the underside thereof to cover the entrances to said passageways when moved by said plate into contact therewith.

19. The apparatus defined in claim 18 wherein said plate is made of a magnetizable material and wherein said additional means further includes a pair of magnets mounted beneath and in proximity to said plate intermediate said shaft and said transducer valves.

20. Gas-flow apparatus connected between first and second inlet channels and first and second outlet channels, said apparatus comprising: first valve means operable in response to a first gas pressure signal to respectively couple the first and second inlet channels to the first and second outlet channels; second valve means operable in response to a second gas pressure signal to respectively couple the first and second inlet channels to the second and first outlet channels; and temperature-pressure transducer means coupled to said first and second valve means and to relatively high and low gas pressure sources, said transducer means including additional means operable in response to ambient temperature conditions to produce said first gas pressure signal and apply it to said first valve means and said second gas pressure signal and apply it to said second valve means.

21. The apparatus defined in claim 20 wherein said first and second valve means include a plurality of valves and gas flow channels interconnected to form a four-terminal bridge circuit between the inlet and outlet channels.

22. In an air-conditioning system, apparatus coupled between first and second inlet channels and first and second outlet channels, said apparatus being operable in response to changes in the operating conditions of the air-conditioning system to change the connections between said inlet and outlet channels, said apparatus comprising: valve means operable in response to a first gas pressure signal to respectively connect the first and second inlet channels to the first and second outlet channels and operable in response to a second gas pressure signal to respectively connect the first and second inlet channels to the second and first outlet channels; and temperature-responsive means for producing said first gas pressure signal when the air-conditioning system is in a heating mode and said second gas pressure signal when the air-conditioning system is in a cooling mode, said temperature-responsive means being coupled to said valve means to apply said first and second signals thereto.
